GRINDING MILL

William F. Heller, Manhasset, N. Y.

Application November 8, 1940, Serial No. 364,787

1 Claim. (Cl. 83—10)

My present invention relates to grinding mills, and more particularly to fine grinding mills for grinding, refining, or reducing sugar, cocoa, chocolate and like substances.

The principal object of my invention is to provide a simple machine for breaking down and grinding sugar, cocoa and the like.

Another object of my present invention is the practical use of non-metallic grinding elements which will be self sharpening.

In the accompanying drawing:

Fig. 1 is a central sectional elevational through a machine embodying my invention, taken on the line I—I of Fig. 2.

Fig. 2 is a plan view of part of the machine, including a portion of the tank and a sectional view through the grinding wheel, and showing the relation existing between the width of the flat grinding slab and the diameter of the annular grinding wheel.

In the accompanying drawing, and in particularly Fig. 1, 10 designates a tank, preferably rectangularly in shape, and steam jacketed as indicated at 11. This tank may be of any suitable size, and arranged in the bottom thereof is a grinding element preferably comprised of a stone slab 13, the upper surface forming the grinding face.

On the top of the tank 10 rest rails 14 (only one being shown) and in these rails run the wheels 15 secured to the bottom surface of a platform or carriage 35. The platform or carriage 35 has mounted thereon and extending therethrough a support 16 in which is formed a vertical bearing 17. In the bearing 17 is rotatably mounted a shaft 18 threaded at its lower end 19. To the lower threaded end 19 is secured a hollow, cylindrical holder 20 by means of a threaded boss 21 attached to the cylindrical holder 20 by radially extending members 22 forming impeller blades for forcing the material to be ground downwardly as viewed in Fig. 1.

In the lower face of the cylindrical holder 20 is secured an annular disc-like grinding wheel 23 the lower face of which cooperates with the upper face of the grinding slab 13.

On the upper end of the shaft 18 is mounted a member 24, this member being an adjustable bearing sleeve housing 25 formed in the support 16. Handles 26 are provided to rotate the bearing sleeve 24 and thus adjust the grinding wheel 23 toward and from the grinding slab 13. Secured to the shaft 18 is a V-belt pulley 26.

Also mounted on the platform or carriage 35 is a support 27 on which is mounted a motor 28.

The driving shaft 29 of the motor 28 has secured thereto a V-belt pulley 30, the grooves of which are in alignment with the grooves of the pulley 26. A belt (not shown) transmits power from the motor 28 to rotate the shaft 18 and attached grinding wheel 23.

The diameter of the annular disc-like grinding wheel 23 is preferably larger than the width of the grind-slab 13. The length of the grinding slab 13, compared to the length of the interior of the tank 10, is such that the clearance between the ends of the grinding slab 13 and the inner end walls of the tank 10, will permit the annular disc-like grinding wheel 23 to overlap the ends of the grinding slab 13 so as to permit the under or grinding face of the grinding wheel to engage with every portion of the upper, or grinding face, of the slab 13. By this construction of the device, each of the grinding faces of the grinding wheel 23 and the slab 13 act as a leveling or trueing means for the other.

Suitable means not shown in Fig. 1) is provided for reciprocating the carriage 35 so as to move the annular disc-like grinding wheel 23 alternately from one end of the tank 10 to the other end thereof. This means may be an automatic and mechanical means, or manual means, but as such type of means is well known in the art, for the sake of simplicity and clearness, the same has not been shown.

Further power for the motor 28 may be provided from any suitable source of power.

The radially extending members 22 are so formed as to provide impeller means for feeding the material to be ground downwardly through the center of the annular disc-like grinding wheel 23 into engagement with the upper grinding face of the slab 13.

In operation, the material to be ground, such as sugar, cocoa, chocolate and the like is placed in the tank 10, to a depth greater than the upper rim of the cylindrical holder 20, and power turned into the motor 28, thus rotating the grinding wheel 23. By manipulation of the handles 26 the bearing sleeve is rotated to bring the lower surface of the grinding wheel 23 into proper grinding relation with the upper grinding surface 13 of the slab 13.

As the grinding wheel rotates and simultaneously reciprocates from one end to the other of the tank 10, the impeller blades 22 force the material through the grinding wheel 23 and between the same and the grinding surface of the slab 13. The material to be ground is thus continually circulated through the grinding mecha-

nism until the proper degree of fineness is obtained, after which the ground material is removed from the tank.

While I have described the preferred embodiment of my invention somewhat in detail, it is to be understood that I may vary the size, shape and arrangement of parts comprising the structure within relatively wide limits without departing from the spirit of the invention.

I claim:

An improved grinding machine comprising, a rectangular tank, a rectangular flat grinding stone mounted in the bottom of the tank, a track-way mounted on the top of the tank, a carriage

5 mounted for reciprocating movement thereon with respect to the tank, a rotatably mounted vertical shaft on the carriage, a tubular holder carried by the shaft, an annular grinding stone mounted on the lower end of said holder and in grinding relation with the face of the first said grinding stone, said holder extending upwardly from the annular grinding stone and terminating below the material level in the tank, means with-
10 10 in the holder for feeding material outward between the grinding surfaces, and means for driving the shaft to rotate the annular grinding stone.

WILLIAM F. HELLER.
